GIRL'S OVERCOAT

Milton Rosenbloom, Forest Hills, N. Y.

Application December 3, 1953, Serial No. 27,906

Term of patent 7 years

(Cl. D3—4)

To all whom it may concern:

Be it known that I, Milton Rosenbloom, a citizen of the United States and a resident of Forest Hills, in the county of Queens and State of New York, have invented a new, original, and ornamental Design for a Girl's Overcoat, of which the following is a specification, reference being had to the accompanying drawing, forming a part thereof, wherein:

Fig. 1 is a front view of a girl's overcoat;

Fig. 2 is a rear view of the same; and

Fig. 3 is an enlarged inner plan view thereof, showing my new design.

The dominant feature of my design resides in the multi-ruffled interior as particularly shown in Fig. 3.

I claim:

The ornamental design for a girl's overcoat, substantially as shown and described.
